UNITED STATES PATENT OFFICE.

ABIJAH J. ALEXANDER AND ISAAC B. ALEXANDER, OF HARTSVILLE, SOUTH CAROLINA.

BOTTLE-VENDING MACHINE.

No. 882,858.

Specification of Letters Patent. Patented March 24, 1908.

Application filed February 7, 1907. Serial No. 356,213.

To all whom it may concern:

Be it known that we, ABIJAH J. ALEXANDER and ISAAC B. ALEXANDER, citizens of the United States, residing at Hartsville, in the 5 county of Darlington and State of South Carolina, have invented certain new and useful Improvements in Bottle-Vending Machines; and we do hereby declare the following to be a full, clear, and exact description 10 of the invention, such as will enable others skilled in the art to which it appertains to make and use the same.

This invention relates to coin-controlled apparatus or automatic vending machines, 15 and more especially to a machine for dispensing bottled wares, such for example as soda-water, ginger-ale and similar beverages. The machine is also adaptable for vending or dispensing other packages or articles.

20 The principal object of the invention is to provide a simple, efficient and practicable machine of the character and for the purpose stated, more particularly for the special purpose of storing and dispensing bottled wares.

25 Another object is to provide for refrigerating the bottles or packages contained in the machine until such time as they are delivered to the purchasers.

With the foregoing objects in view, the 30 invention will hereinafter be fully described by reference to the accompanying drawings (which are to be taken as a part of this specification), and then more particularly pointed out in the claims following the description.

35 It is not desired, however, that the invention should be understood as essentially limited to the specific construction illustrated, as it is obvious that the same may be embodied in other equivalent forms, and that alterations 40 in details of structure and arrangement of parts may be made without departing from the scope of the invention.

In said drawings, Figure 1 is a perspective view of a complete machine, with a portion 45 of its casing broken away to expose the interior construction. Fig. 2 is a vertical section of the same, said section being taken on a line from front to rear of the machine. Figs. 3, 4, 5 and 6 are detail views of the coin-controlled device.

As shown, the machine comprises, in the main, a refrigerator-casing having mounted therein a revoluble drum which is controlled by the coin-operated device for delivering 55 the bottles, the latter being fed to the drum from a reservoir wherein the bottles are

directly exposed beneath the ice in the refrigerator.

The letter A denotes the casing, which may be of any appropriate structure and conformation, and which may be ornamented or embellished in any manner desired. In the illustration it has the appearance of an ordinary square or box-like structure, with an indentation at the front provided with a 60 curved glass door or cover B overlying the front of the drum C and adapted to display the bottles or packages carried thereby. In the construction of the casing, the designer may avail himself of any of the well-known 65 or improved devices and materials generally used in refrigerator construction. Within the casing, the revoluble drum C is desirably mounted to turn on ball-bearings. The drum is provided on its periphery with a 70 series of longitudinal pockets c, each adapted to receive and loosely hold or inclose one of the bottles or packages to be delivered. These pockets are or may be formed by any 75 suitable partitions arranged between the projecting rims of the opposite sides of the drum.

Above the drum, there is an inclined feed-chute D, into and down which the bottles roll or pass from a space or chamber E, preferably in the upper back part of the casing. 80 Said feed-chute D and chamber E constitute a storage-reservoir, into which the bottles are introduced by inserting them through a door F. The front or lower end of the feed-chute has a downwardly-curved mouth d, located 85 for delivering the bottles to the drum approximately above the axis of rotation or preferably slightly in advance thereof. The bottles drop by gravity one by one into the pockets of the drum, as the latter is turned 90 or revolved step by step, as hereinafter explained.

Above the feed-chute is an open-bottomed ice-chest or chamber G, wherein the ice for 100 refrigerating or cooling the bottles may be supported by any suitable means, as upon a well-known form of ice-tray adapted to set within the ice-chest; the ice being introduced into the chamber through a door H. The upper side of the feed-chute comprises a grating, screen or other reticulated plate d', which, besides preventing the bottles from 105 rolling over or upon one another as they pass down the side, also allows the descent of cold air from the ice upon the subjacent bottles in the feed-chute as well as those carried by the drum; thereby keeping them cold and 110

well-preserved. A drip-pan or receptacle I is provided below the drum to receive the drippings from the ice. The cold water or drippings may drop directly through the 5 grating or reticulated plate d' and trickle over the bottles stored in the feed-chute, and then flow over the front of the drum and bottles carried thereby (the partitions between the pockets c being perforated or 10 reticulated for that purpose), and drop finally into the drip-pan; or, if preferred, the ice-chest or chamber may have in its bottom any suitable provision for collecting the water and conveying it through a pipe to the 15 drip-pan; as, for example, an elevated pan or shield under the tray or supports for the ice, such devices being well-known in refrigerator-constructions. In either event, whether the cold water trickles down over the bottles, 20 thereby promoting the refrigeration, or whether the water is collected in the ice-chamber and otherwise discharged therefrom, the supply of bottles in the feed-chute D and those in the drum C are exposed to the 25 descending cold-air currents from the ice, thus cooling and preserving the bottles while stored in the machine and until they are dispensed or ejected by manipulation of the coin-and-slot device hereinafter described.

30 The upper front portion of the casing, adjacent to the ice-chamber, is or may be occupied by a supplemental refrigerator-chamber J, having access through a door K, for general purposes, or for storing and keeping cool a reserve supply of bottles, or any other articles which it may be desired to keep on hand.

In the front of the casing, there is an exit opening of appropriate size to admit the 40 passage of one bottle, for delivery to the purchaser. Said opening, located adjacent to the front periphery of the drum and desirably slightly below its axis of rotation, is or may be closed by a swinging door or gate L, 45 adapted to be pushed open by the bottle delivered from the drum, and adapted to close by gravity or otherwise; so as to keep the refrigerator closed. The bottle may be delivered upon or in any suitable receiver, as 50 a table, receptacle or curved holder M, as shown in the drawings.

The drum C is revolved forwardly by the weight of the bottles carried thereby between the feed-chute D and exit-door L, and it is 55 controlled by a suitable coin-operated device or coin-and-slot mechanism N adapted, when operated with an eligible coin, to intermittently release said drum and permit it to advance or turn one step; there being one 60 movement of the drum for each operation of said coin-actuated device.

At each turn of the drum, a bottle drops from the feed-chute D into the subjacent empty pocket or receptacle c, which has been 65 brought under the mouth d of said feed-

chute; and, at the same time, the foremost bottle carried by the drum rolls from its pocket against the swinging door L and out upon or into the receiver M, the pocket from which the bottle emerges having just been 70 brought in opposition to said exit-door. After such operation, the drum is held fixed or stationary until a subsequent manipulation of the coin-controlled mechanism. In this connection, it will be understood that any 75 suitable coin-controlled mechanism may be employed for operating, releasing or controlling the drum; but, as a part of the invention, we have devised the improved mechanism shown in the drawings, a description of which 80 is as follows:

1 denotes the knob or head of a push-rod or plunger 2, which is slidably fitted in a bore or opening therefor in a body 3, which body may be a part of the casing A, or a projection 85 or attachment thereon, as a block or casting of wood, metal or other material. The plunger is normally held outward or forward by a spring 4, shown in the present example as a coiled spring inclosed within the plunger, the latter being hollow or tubular, the said spring acting between the knob or plunger-head 1 and a fixed pin 5 entered through a longitudinal slot 6 in the hollow plunger.

7 denotes a slot for introducing a coin, as a 95 nickel, dime, quarter or other sized coin x intended for operating the machine. Said slot 7 extends vertically into a subjacent recess 8 in the block or body 3. The plunger 2 projects into and through said recess 8, and has in its side a cross slot 9 which in the normal position of the plunger registers with one side or approximately one-half of the coin-slot 7. Upon dropping an eligible coin (one of proper size and denomination) into the 105 slot 7, the coin will drop down into the recess 8 and into the cross-slot 9 in the plunger, so that a substantial portion of the coin is engaged by the plunger, while a substantial portion is free in the recess 8, the latter being of appropriate size and shape to accommodate the plunger and the coin projecting from its side. After inserting the coin, the purchaser pushes the knob or plunger-head 1, whereby the plunger 2 carries the coin engaged thereby inwardly and drops it, either 110 directly into a receptacle or into a coin-chute 10 for delivering it to the money-box 11. As the coin is thus pushed inward, it engages and snaps past the beveled end 12 of a spring- 115 actuated trigger 13, having a detent or catch 14; and the coin thus displaces the trigger, which, however, immediately snaps back to normal position under the influence of its spring 15. The trigger 13, through its 120 detent 14, normally holds the drum C fixed or stationary (as by engaging under the partitions under the pockets c, or otherwise engaging suitable catches, notches or projections c' at suitable intervals on the drum); 130

but when the trigger is displaced by the coin, pushed inward by the push-rod, the detent being displaced permits the drum to move one step, so as to deliver a bottle through the 5 exit-door L; further movement of the drum being prevented by the detent regaining its normal position in time to engage the next catch c' on the drum. By this means, the 10 automatic delivery of the bottle is obtained by inserting or dropping a proper coin into the slot, and pushing the plunger. If a coin of larger size than necessary is attempted to be used, it will of course be impossible to use it, since the slot 8 is only of sufficient width 15 to accommodate a coin of requisite dimension. In the event of inserting a smaller coin (as a penny or dime when a nickel is required), provision is made for returning such ineligible coin to its owner. For this purpose, a slot 16 extends downward from the recess 8, substantially as a continuation of the slot 7 but of slightly less width. Hence, 20 a coin of smaller size than requisite will simply drop down through the slots 7 and 16 25 and pass out through the bottom, falling upon or into the receiver M, or elsewhere as desired.

The mode of operation of the machine having already been explained in detail, it 30 will be sufficient to summarize as follows: The machine is made ready for service by filling the bottle-reservoir (comprising the feed-chute D and introducing-chamber E), and by causing a step-by-step rotation of the 35 drum C sufficient to place bottles in the several pockets of the drum between the delivery-mouth d of the feed-chute and the exit-door L of the case. A purchaser desiring to obtain a bottle drops a nickel (or 40 whatever coin may be charged) into the slot 7 and pushes the knob 1 of the plunger 2, whereby the trigger 13 releases the drum and allows it to rotate one step, thus depositing a bottle through the exit L and upon or into 45 the receiver M, while simultaneously another bottle is fed from the feed-chute D into the pocket c of the drum next brought under the mouth of said feed-chute.

We claim as our invention and desire to secure by Letters Patent of the United States: 50

1. In an automatic vending machine, the combination of a casing, a revoluble carrier-drum mounted therein adapted to hold bottles or packages arranged lengthwise on the periphery of the drum, a superposed inclined 55 feed-chute having a mouth arranged for discharging the bottles or packages one at a time to the drum as it is successively turned under said mouth of said feed-chute, an open-bottomed ice chamber above said chute, a normally closed exit through which the bottles are one at a time delivered from the drum as it successively turns past said exit, and means for controlling motion of the 60 drum. 65

2. In a bottle-vending machine, the combination of a casing, an ice-chamber therein, an inclined feed-chamber under and adjacent to said ice-chamber in which the bottles are arranged side by side, being exposed to cold from the ice-chamber, a carrier-drum having its periphery spaced to hold bottles and arranged to revolve under the mouth of said feed-chute, an exit in the casing through which the bottles are delivered from the 75 drum, and means for controlling motion of the drum. 70

3. In a bottle-vending machine, the combination of a casing, a revoluble carrier-drum therein adapted to receive bottles at its top 80 and to deliver them from its front, a feed-chute above the drum for feeding the bottles thereto, an ice-chamber above said feed-chute, a chamber behind said ice-chamber for introducing the bottles, a supplemental refrigerator-chamber in front of said ice-chamber, an exit for the bottles in the front of the casing, and means in connection with the drum for controlling the motion thereof. 85

In testimony whereof we affix our signatures, in presence of two witnesses.
